UNITED STATES PATENT OFFICE.

ARTHUR J. MEALAND, OF CANTON, OHIO.

NOVELTY ENTERTAINMENT DEVICE.

1,099,188.

Specification of Letters Patent.

Patented June 9, 1914.

Application filed March 4, 1914. Serial No. 822,366.

To all whom it may concern:

Be it known that I, ARTHUR J. MEALAND, a citizen of the United States, residing at Canton, in the county of Stark and State of Ohio, have invented a new and useful Novelty Entertainment Device, of which the following is a specification.

My invention relates to improvements in devices adapted to afford entertainment, and 10 more particularly to a device in which the elements of uncertainty and humor are so involved as to produce an interesting diversion, especially adapted for the entertainment of social gatherings.

15 The objects of the invention are, to produce a novel entertainment device in the use of which a number of individuals may separately take part for the entertainment of the entire gathering, the individual taking such part being uninformed of the full effect and meaning of his acts until after the same are completed, and such acts necessarily resulting in unusual or comic expressions well suited to the entertainment of 25 those present. These objects, together with other objects readily apparent to those skilled in the art, may be attained by the construction illustrated in the accompanying drawings, although the invention may 30 be embodied in other forms, the construction illustrated being chosen by way of example.

In the drawings Figure 1 is a perspective view of a book embodying my invention. Fig. 2 is a plan view of a portion of one of the pages of said book.

Throughout the several views similar reference numerals indicate similar parts.

More specifically describing the construction disclosed in said drawings, the numeral 1 indicates the front cover and the numeral 2 the back cover of a book provided with a plurality of leaves arranged in pairs, each pair comprising a first, apertured leaf 3 and 45 a second, unapertured leaf 4, said leaves being provided with uncut edges at 5.

The second leaf of each pair is provided, upon the front page thereof, with an incomplete novel or humorous sketch, said sketch being incomplete by reason of omitted portions where are arranged blank spaces. In the first leaf of the pair are arranged apertures which register with the blank spaces in said sketch in such way that 55 as the pair of leaves is viewed before the edge at 5 is cut none of the said sketch appear-

ing on the second leaf is visible. This condition is illustrated in Fig. 1, in which the blank spaces 6 on the second leaf are visible through the apertures 7 of the first leaf. 60

Appearing on the front page of the first leaf are brief directions adapted to guide the individual in filling the various spaces in such way as to serve to complete the sketch on the second leaf in accordance with 65 the context of the sketch. In this connection it should be noted that certain suggestions or incomplete words or figures may, if desired, appear in the spaces 6, as for instance, the initial letters M. A. appearing in 70 the space disclosed by that aperture below the direction "A favorite actress" or the small picture of a dagger in the space reserved for the picture of the individual, as shown at the lower left-hand corner of the page. 75

Various general plans for the preparation of such a book may be carried out, various pairs of leaves being especially adapted for particularly designated individuals. The pair of leaves illustrated in the drawing is 80 especially adapted to be used by a young lady, the text of the sketch being especially adapted accordingly.

In using the book, such as described, the spaces 6 should be filled in with pen or pencil in accordance with the directions accompanying the apertures and when all of the spaces have been filled in the edge at 5 may be cut, permitting the disclosure of the completed sketch on the second leaf. It should, 90 of course, be understood that no attempt should be made to read the incomplete sketch before filling in the spaces, for by so doing the element of uncertainty and consequent humorous results would be avoided. 95

In the entertainment of a social gathering it will be understood that any desired number of the pairs of leaves may be used or filled in by various individuals before cutting the edges of any of the pairs. When 100 all of said individuals have filled in the spaces of the various sketches, the leaves may be cut and the various sketches read to the assemblage, producing a harmless and jolly form of entertainment for all concerned. 105

Although the drawings and above specification disclose the best mode in which I have contemplated embodying my invention, I desire to be not limited to the details 110 of such disclosure, for many changes in form and construction may be made, as cir-

cumstances require or experience suggests, without departing from the spirit of the invention, within the scope of the appended claims.

5. I claim:—

1. An entertainment device comprising first and second members, the second member provided with a work rendered incomplete by a blank space, the first member detachably connected to said second member, adapted to conceal said work and provided with an aperture corresponding to said blank space, and said blank space adapted to be filled in through said aperture.

10 2. An entertainment device comprising first and second members, the second member provided with a work rendered incomplete by blank spaces, the first member detachably connected to said second member, and provided with apertures corresponding to said blank spaces, directions for filling said spaces disclosed upon said first member, and said apertures adapted to permit the filling of said spaces without the disclosure of the said work when said members are connected together.

15 3. In a device of the character mentioned, a pair of leaves uncut at the edge and constituting first and second connected leaves, the second leaf provided with a literary or artistic sketch provided with blank spaces rendering said sketch incomplete, the first leaf provided with apertures adapted to register with said spaces and adapted to 20 permit the filling of said spaces without the disclosure of the incomplete sketch, and said leaves adapted to be separated from each other by cutting said uncut edge, after 25 said spaces have been filled, whereby to 30 close the completed sketch upon said second leaf.

4. In a device of the character described, a pair of leaves detachably connected to each other and constituting first and second connected leaves, the second leaf provided with a sketch provided with blank spaces rendering said sketch incomplete, the first leaf provided with apertures adapted to register with said spaces and adapted to permit the filling of said spaces without the disclosure 45 of the incomplete sketch, directions for guidance in filling said spaces appearing on said first leaf and said leaves adapted to be separated from each other, after said spaces have been filled, whereby to disclose the 50 completed sketch upon said second leaf.

5. In a device of the character described, a first, apertured member and a second, unapertured member detachably connected to said first member, said second member provided with a work adapted to be concealed by said first member when said members are 55 connected together, and further provided with a space registering with the aperture in said first member when said members are 60 connected together, a fragment appearing in said space and adapted to be utilized as a portion of work filled into said space, directions appearing on said first member for guidance in filling said space in accordance 65 with the undisclosed work on said second member, and said members adapted to be detached after said space has been filled, whereby to disclose the completed work upon said second member.

In testimony that I claim the above, I have hereunto subscribed my name in the presence of two witnesses.

ARTHUR J. MEALAND.
